NURSING BOTTLE HOLDER

Marie E. De Clerck, Detroit, Mich.

Application January 22, 1949, Serial No. 387

Term of patent 14 years

(Cl. D83—8)

To all whom it may concern:

Be it known that I, Marie E. De Clerck, a citizen of the United States, residing at 613 Eastlawn Avenue, Detroit, in the county of Wayne and State of Michigan, have invented a new, original, and ornamental Design for a Nursing Bottle Holder, of which the following is a specification, reference being had to the accompanying drawing, forming a part thereof.

In the drawing:

I claim:

The ornamental design for a nursing bottle holder, substantially as shown.

MARIE E. DE CLERCK.
